UNITED STATES PATENT OFFICE.

JOSEPH E. SMITH, OF ERDENHEIM, PENNSYLVANIA.

BOOT AND SHOE.

1,102,096.

Specification Letters Patent. Patented June 30, 1914.

Application filed October 22, 1913. Serial No. 797,013.

To all whom it may concern:

Be it known that I, JOSEPH E. SMITH, a citizen of the United States, residing at Erdenheim, in the county of Montgomery and State of Pennsylvania, have invented certain new and useful Improvements in Boots and Shoes, of which the following is a specification.

My invention relates to improvements in boots and shoes and more particularly to an improved arrangement of removable wearing disks secured in the sole and heel and capable of being removed and replaced when worn.

15 A further object is to provide improved socket pieces located in the outer sole and in the outer thickness of the heel, and secured between the outer and the inner soles and providing a receptacle for a disk holding member screwed into the socket and capable of being removed and replaced when the wearing disk is worn.

20 A further object is to provide improvements of this character which enable the owner of a pair of shoes to replace worn disks by new ones, so that he can maintain a good sole on the shoe for an indefinite period, hence overcoming the necessity for having the shoes half soled and heeled, and furthermore provide improved wearing disks which prevent slipping and cushion the contact of the shoe on the ground, embodying the advantages of rubber soles and heels.

25 With these and other objects in view, the invention consists in certain novel features of construction and combinations and arrangements of parts as will be more fully hereinafter described and pointed out in the claims.

30 In the accompanying drawings: Figure 1 is a bottom plan view illustrating one form of my improvements. Fig. 2 is a view in section on an enlarged scale on the line 2—2 of Fig. 1. Fig. 3 is a perspective view of 35 one of the socket members. Fig. 4 is a view similar to Fig. 2 illustrating a modification. Fig. 5 is a bottom plan view of the modification illustrated in Fig. 4. Fig. 6 is a view in transverse section on the line 6—6 of Fig. 7 40 illustrating another modification, and Fig. 7 is a bottom plan view of a shoe heel illustrating the modification shown in Fig. 6.

45 1 represents a boot or shoe sole and 2 the heel. The outer sole 1 is provided with 50 openings 3 in which socket members 4 are located. These socket members 4 are cylin-

drical in cross section and fit the openings 3. They are provided at opposite sides with lugs 5 which project between the insoles 6 and the outer soles 1, and have spurs 7 at 55 their free ends projecting at right angles and forced into the outer sole 1 as clearly shown in Fig. 2 so that by reason of these spurs the socket members are prevented from rotary movement. The socket members 60 65 4 are internally screw-threaded as shown at 8 to receive disk carrying members 9. These members 9 are cylindrical in form and externally screw-threaded to mesh with the screw-threads in the socket member 4. The 65 disk carrying members 9 contain disks 10 which are preferably of rubber, although they may be of any other suitable material. The disks 10 at their outer ends are reduced in diameter and project through an internal 70 75 annular flange 11 at the outer end of the member 9.

70 By forming the disk of two diameters as above explained, a shoulder 12 is provided which bears against the flange 11 and by 80 reason of this construction, the disk is securely confined in the socket. The flange 11 is provided in opposite sides with notches 13 so that the member 9 will be readily manipulated by a spanner wrench in assembling the 85 parts, and by an ordinary screw-driver to remove the member 9 when the disk 10 is worn down flush therewith.

80 It is of course to be understood that the disk 9 projects sufficiently beyond the surface of the sole to sustain the wear, and I 90 would have it understood that the invention is not limited to any particular number or arrangement of these disks as they may be variously located in the sole and in the heel. 95

95 The devices are located in the heel in the same manner as in the sole except, of course, they are located in the outer thickness only, as heels often have a number of different thicknesses, while the soles usually have but 100 the two.

100 In the modification illustrated in Fig. 4, the socket member 4 is precisely like the socket member illustrated in connection with Figs. 1, 2, and 3, but instead of providing a 105 disk holding member 9 and a rubber or similar disk 10, I provide a leather disk 14 which is cemented or otherwise secured to the outer surface of a disk carrying member 15.

110 The disk carrying member 15 constitutes a screw-threaded plug which is screwed into the socket 4, and is provided in its outer sur-

face under the disk 14 with a screw-driver receiving groove 16 which is exposed when the disk 14 is worn down, so that the member 15 may be removed and a new disk ⁵ place the same.

The modification illustrated in Figs. 6 and 7 is particularly adapted for use in connection with old shoes or shoes manufactured in the ordinary way. In this modification, I provide metal plates 17 which are countersunk in the surface of the shoe and secured by nails or other securing devices 18. These plates 17 have screw-threaded sockets 19 into which disk carrying members 15 may be screwed.

It is of course to be understood that any form of disk may be employed such as shown in Fig. 2 or Fig. 4, and while I have indicated certain desirable materials, I would ²⁰ have it understood that the invention is not limited to the particular materials employed, and various slight changes might be made in the general form and arrangement of parts described without departing from my invention, and hence I do not limit myself to the precise details set forth but consider myself at liberty to make such changes and alterations as fairly fall within the spirit and scope of the appended claims.

³⁰ Having thus described my invention, what I claim as new and desire to secure by Letters Patent is:

1. A device of the character described, comprising a cylindrical socket member having a closed top and internally screw-threaded throughout its length, a cylindrical in-

sert holding member externally screw-threaded throughout its length, and of the same length as the internal longitudinal dimension of the socket member, said insert ⁴⁰ holding member having an internal annular flange at its outer edge, and an insert of cylindrical shape having two portions of larger and smaller diameter, respectively, the larger portion fitting the disk holding ⁴⁵ member and extending longitudinally from the flange to the bottom of the socket member, the smaller portion of said insert projecting through the flange and below the edge of the socket member, substantially as ⁵⁰ described.

2. A device of the character described, comprising a cylindrical socket member having a closed top and internally screw-threaded throughout its length, a cylindrical holding member externally screw-threaded throughout its length, and of the same length as the internal longitudinal dimension of the socket member, and a ground engaging member, said holding member at its ⁵⁵ upper end bearing against the upper end of the socket and holding the ground engaging member in position to project the same below the socket member, substantially as described.

In testimony whereof I have signed my name to this specification in the presence of two subscribing witnesses.

JOSEPH E. SMITH.
